UNITED STATES PATENT OFFICE.

AMOS H. SMITH, OF NEW YORK, N. Y., ASSIGNOR TO AMERICAN BANK NOTE COMPANY,
A CORPORATION OF NEW YORK.

NUMBERING-HEAD.

1,132,493.

Specification of Letters Patent. Patented Mar. 16, 1915.

Application filed June 25, 1912. Serial No. 705,786.

To all whom it may concern:

Be it known that I, AMOS H. SMITH, a citizen of the United States, residing in the borough of Bronx, in the city, county, and 5 State of New York, have invented certain new and useful Improvements in Numbering-Heads, of which the following is a specification, reference being had therein to the accompanying drawings, which form a part 10 thereof.

My invention relates to improvements in numbering heads, and more particularly to means for preventing the accidental actuation of a digit wheel of higher denomination 15 by a similar wheel of next lower denomination.

The main object of the invention is to provide a numbering head wherein the transfer mechanism will successively actuate the 20 digit type wheels, and wherein these wheels will be normally locked in a manner to prevent the actuation of any digit wheel resulting in the accidental actuation of an adjoining digit wheel of next higher or lower 25 denomination, while being automatically released as the transfer mechanism becomes operative in relation thereto.

A further object is to provide a locking mechanism which will be effective to prevent the rotation of any digit wheel excepting the units or primary wheel at all times except when the transfer mechanism is operative in relation to a particular wheel.

A still further object is to provide a numbering head wherein each of the digit wheels will be normally locked by a mechanism under the control of the digit wheel of next higher or lower denomination, so as to insure a timely release of the locking mechanism.

A still further object is to provide a numbering head wherein when any digit wheel of higher or lower denomination shall be unlocked at a time when the transfer mechanism is not about to become operative with relation thereto, there will be positioned between said wheel and the unit or primary wheel, at least one digit wheel which will be locked so as to prevent the accidental actuation of the unlocked wheel. And a still further object is to provide a numbering head of this character embodying therein an automatically acting mechanism which will lock and release the various digit wheels as required, and which may be applied to the

ordinary numbering head without interfering with the other operative parts thereof, or necessitating a change in the design or dimensions of the head.

The invention consists primarily in a numbering head embodying therein a plurality of independent, digit type wheels, a transfer mechanism whereby said wheels are successively rotated in carrying from one denomination to another, locking means normally holding all of said wheels excepting the unit or primary wheel against rotation, and means operative by the wheels in their sequence of operation whereby said locking means will be rendered inoperative as each wheel is actuated in its order by said transfer mechanism; and in such other novel features of construction and combination of parts as are hereinafter set forth and described, and more particularly pointed out 75 in the claims hereto appended.

Referring to the drawings:—Figure 1 is a plan view of a number head embodying my invention, a portion thereof being shown in section; Fig. 2 is a side view of one wheel, taken on the line 2—2 of Fig. 1; Fig. 3 is a side view of an adjoining wheel, taken on the line 3—3 of Fig. 1; Fig. 4 is a perspective view of the shaft; and Fig. 5 is a front view of the head, showing the transfer 85 mechanism.

Like letters refer to like parts throughout the several views.

In numbering heads there is a tendency of the ink to enter between adjoining wheels and cause the rotation of a wheel of one denomination to turn the wheel of another denomination with a resultant loss of the arithmetical progression of the numbers printed. If the head be used in an ascending progression, a wheel of higher denomination is liable to be thus accidentally actuated, while if in a descending progression a wheel of lower denomination is liable to be thus accidentally turned. Inasmuch as accuracy is essential to certain lines of work, as bank notes, bonds, stock certificates, drafts, checks, etc., in order not to spoil an edition or series, a numbering head wherein such an accidental actuation of a wheel out of its order cannot occur is desirable.

In the accompanying drawings, I have shown my invention applied to a numbering head of well known construction.

In the said drawings a indicates a U.

shaped frame, carrying a fixed shaft b which is provided with the usual angular recess b' for permitting the dropping of the cipher below the printing plane. Loosely mounted upon the shaft b is a plurality of digit printing wheels c, c', c^2, c^3, c^4 and c^5 , the first of which wheels is the unit or primary wheel through which all of the other wheels are actuated in their order. In the machine shown in the drawings, the numbers are printed in an ascending progression, and the following description will have reference to a machine of this type, it being understood, however, that this mechanism 5 may be reversed to have the head print in a descending progression, as when it is desired to have the numbered articles arranged in piles with the lowest number uppermost. Each of the wheels $c, c', c^2, c^3, c^4, c^5$ is provided with a ratchet $d, d', d^2, d^3, d^4, d^5$, engaged by a spring pressed pawl $e, e', e^2, e^3, e^4, e^5$, and adapted to accurately position each wheel for printing and hold it against movement while the types are being inked. 10 Each of said wheels is provided with printing type from 0 to 9, there being a ratchet for each character.

Mounted in the frame a is an impact plunger f adapted to actuate the unit or primary 15 wheel c by means of the spring pressed pawl g coöperating with the ratchet d , and the transfer mechanism which will be more fully described hereinafter. Said pawl and said transfer mechanism are carried, and 20 actuated, by an oscillatory frame h under the control of the plunger f .

The transfer mechanism comprises a graduated series of pawls g', g^2, g^3, g^4 which together with the pawl g are pivoted upon the 25 frame h and are spring pressed toward the wheels c' to c^4 inclusive. All of these pawls act in unison, and are adapted to enter recesses i in each of the wheels c' to c^4 inclusive, the varying heights of these pawls determining the operative relation of the transfer mechanism to the wheels adapted to be 30 actuated during the transfer operation. For instance, if the figure 9 upon the unit or primary digit wheel c be in the printing position, the pawl g will enter the recess i in this wheel, thus permitting the pawl g' to engage the ratchet of the wheel c' , the remaining pawls g^2 to g^4 being thus held out of engagement with their respective ratchets 35 and prevented from assuming the operative relation to their wheels. The pawls g' to g^4 , with the continued operation of the head, will successively drop into the recess i' in their respective ratchet wheels, thus causing 40 the pawl actuating a wheel of lower denomination, to normally hold the pawls of higher denomination out of engagement with their wheels, but permitting such engagement once during each rotation of such wheel of 45 lower denomination.

The mechanism heretofore described is old and well known in this art, and is merely shown and described as exemplifying a type of numbering head in connection with which my invention is capable of application. In 70 this type of head as now used, all of the digit wheels are capable of being simultaneously advanced independently of the transfer mechanism, as in case of the accumulation of dried ink between the wheels, and it 75 is to obviate this condition that I have developed my present invention.

In carrying out my invention, I provide the shaft b with a series of peripheral recesses j , one adjacent to each tooth of the 80 ratchet of each digit wheel c' to c^5 inclusive, and mount in this recess a bolt k adapted to be thrust substantially radially of the shaft b by means of a spring k' . Preferably this bolt and spring are made of an integral strip 85 of spring metal with an angular end acting as the bolt k , a construction which lends simplicity to the structure while at the same time affording the desired resistance to the rotation of a digit wheel locked thereby and 90 permitting the necessary compactness of structure. This bolt k is of a width to project across the space between two adjoining digit wheels, thus positioning it so that it 95 will be capable of locking one of these wheels and of being released by the adjoining wheel of lower denomination. Each digit wheel c' to c^5 inclusive upon one side thereof is provided with a plurality of angular recesses or sockets m adapted to be engaged by the bolt k to lock this wheel against 100 rotation in either direction, a recess or socket m being provided for each character carried by the digit wheel. It will thus be observed 105 that when the head is set at zero throughout, every digit wheel excepting the unit or primary wheel will be locked against movement in either direction. To accomplish the release of these digit wheels and permit the 110 free rotation of any wheel under the control of the transfer mechanism only when it is required to carry the wheel of next higher 115 denomination through this mechanism, I provide each of the wheels c to c^4 inclusive upon the side thereof adjacent to the wheel of next higher denomination with an annular channel n about the shaft b , at one point whereof determined by the figure 9 coming to the printing position, is a cam o adapted to engage and depress the bolt k in a manner to actuate this bolt and release the wheel of next higher denomination.

In order to secure the desired result, it is necessary that the bolt k should project from adjacent to one wheel into this channel so as to be engaged by this releasing cam. 120 The operation of the herein described device is substantially as follows: With each impression from the head, the plunger f is 125 depressed and the frame h oscillated to ad- 130

vance the pawl g one tooth and cause its spring to bring it into that relation to the ratchet d to cause the return oscillation of said frame to feed this wheel forward one character. During this operation all of the 5 wheels c' to c^5 are locked by the bolts k , the wheel c^5 in the head shown not being automatically actuated. With the repetition of this operation, the unit or primary wheel c 10 will be advanced until the figure 9 is in the printing position, whereupon the pawl g will drop into the recess i of this wheel c , permitting the pawl g' to engage the ratchet d' of the type wheel c' preparatory to the 15 transfer operation from the wheel c to the wheel c' . As the figure 9 approaches the printing position, the cam o of the wheel c will engage the bolt k controlling the digit wheel c' , which prior to this time has been 20 seated in the channel n of that wheel, so as to permit the free rotation of the wheel c' , and depress it against the tension of the spring k' into the recess j in the shaft b in a manner to cause this bolt to recede entirely 25 from the socket m and thus release the said wheel c' . Upon the return movement of the frame h , the wheels c' will advance one figure in unison, the spring k' upon the completion of this movement forcing the bolt k into the next recess or bolt 30 socket m of the wheel c' and locking this wheel against further movement until the next transfer operation. This operation is repeated, the wheels c to c^4 moving to present 35 numbers in arithmetical progression.

It will be observed that the only wheel moving under power except during the operation of transferring from one wheel to another, is the unit or primary wheel c , and 40 that except when the figure 9 of any wheel is in the printing position, the wheel of next higher denomination is locked against movement. Assuming, however, that the wheel c' in the tens place, has the figure 9 45 in the printing position, the wheel c^2 , in the hundreds place will be unlocked. But unless the wheel c has its figure 9 in the printing position, the wheel c' will itself be locked against movement, so that no accidental 50 movement of the wheel c^2 can occur. In fact, no movement of the wheel c^2 can occur until the figure 9 on both wheels c and c' is 55 in the printing position, whereupon wheels c c' and c^2 which, as stated, is already unlocked, will be simultaneously advanced one figure. Hence even though any wheel c^2 c^3 c^4 or c^5 be unlocked, none of these can be accidentally turned so long as there is at 60 least one wheel between it and the unit or primary wheel c which is locked. While the various wheels c' to c^4 are normally locked, the head may be set to any desired number by turning the wheels in sequence from the wheel c , so as to bring the figure 9 to the 65 printing position in each.

It is not my intention to limit my invention to use with the type of numbering head shown in the drawings, nor to the precise details of construction illustrated, it being apparent that it may be used with various 70 types of heads, and that such details may be varied without departing from the spirit and scope of the invention.

Having described my invention, what I claim as new and desire to have protected 75 by Letters Patent, is:

1. A numbering head embodying therein a main shaft, a sequence of independent digit wheels rotatably mounted thereon, independently operative locking means normally 80 holding each of said wheels of a denomination above the units wheel against rotation, means carried by each wheel of a lower denomination operative upon the locking means of the wheel of next higher denomination 85 whereby said locking means is released when said wheel of higher denomination is to be actuated in its order during the operation of transferring, and all other wheels of higher denomination will remain 90 locked, a main actuating mechanism, means actuated thereby and adapted to act directly upon each digit wheel, and means carried by each digit wheel coöperating with said last named means. 95

2. A numbering head embodying therein a fixed shaft having a plurality of recesses therein, a sequence of independent digit wheels loosely mounted upon said shaft, each of said wheels having a bolt socket for each digit thereon, presented toward said shaft, independently operative depressible locking means mounted in each of the recesses in said shaft and adapted respectively to normally enter the sockets in a digit wheel, 100 means carried by each digit wheel of lower denomination adapted to depress said locking means of the wheel of next higher denomination when transferring from said wheel, of lower denomination to said wheel 105 of next higher denomination, whereby all other wheels of higher denomination remain locked, a main actuating mechanism, means actuated thereby and adapted to act directly upon each digit wheel and means carried by each digit wheel coöperating with 110 said last named means. 115

3. A numbering head embodying therein a fixed shaft, a sequence of independent digit wheels loosely mounted upon said shaft, 120 automatically acting coöperating locking means carried by said shaft and said digit wheels respectively, means carried by each wheel of one denomination operative upon the locking means of the wheel of the next 125 denomination whereby in transferring from one wheel to another only the wheels to be moved in transferring will be free to rotate, a main actuating mechanism, means actuated thereby and adapted to act directly 130

upon each digit wheel and means carried by each digit wheel coöperating with said last named means.

4. A numbering head embodying therein a fixed shaft having a series of recesses therein, a plurality of independent digit type wheels loosely mounted upon said shaft, adjoining wheels projecting over said recesses, a transfer mechanism whereby said wheels are successively rotated in carrying from one denomination to another, the adjoining faces of any two wheels having therein respectively a series of recesses or sockets, one for each figure upon said wheel, and the other said wheel having a channel extending about said shaft with a cam surface projecting into engagement with said shaft at one point thereof determined by the printing position of the figure 9 on said wheel, a bolt seated in each said recess and adapted to enter said socket and said channel, whereby it is adapted to be engaged by said cam, and a spring normally projecting said bolt outwardly.
5. A numbering head embodying therein a fixed shaft having a series of recesses therein, a plurality of independent digit type wheels loosely mounted upon said shaft, adjoining wheels projecting over said recesses, a transfer mechanism whereby said wheels are successively rotated in carrying from one denomination to another, the adjoining faces of any two wheels having therein respectively a series of recesses or sockets, one for each figure upon said wheel, and the other said wheel having a channel extending about said shaft with a cam surface projecting into engagement with said shaft at one point thereof determined by the printing position of the figure 9 on said wheel, a

bolt seated in each said recess and adapted to enter said socket and said channel, whereby it is adapted to be engaged by said cam, and a spring normally projecting said bolt outwardly, said bolt and said spring being formed of an integral leaf spring connected to said shaft and having its free end turned at an angle to form said bolt.

6. A numbering head embodying therein a sequence of digit wheels, means normally locking each of said wheels of a denomination above the units wheel against rotation in either direction, means carried by each wheel, and automatically operative to release the locking means of the adjoining wheel during the transfer operation, a main actuating mechanism, means actuated thereby and adapted to act directly upon each digit wheel, and means carried by each digit wheel coöperating with said last named means.

7. A numbering head embodying therein a plurality of digit wheels, a transfer mechanism, independently operative means preventing the actuation of one wheel by an adjoining wheel, means carried by each digit wheel for releasing an adjoining wheel, at a time when said transfer mechanism is operative thereon, and a main actuating mechanism controlling the units digit wheel and said transfer mechanism.

In witness whereof, I have hereunto affixed my signature, in the presence of two subscribing witnesses, this 21st day of June, 1912.

AMOS H. SMITH.
